UNITED STATES PATENT OFFICE.

JOHN H. RUSSELL AND ASA W. PHELPS, OF SPRINGFIELD, WISCONSIN.

GRINDING-MILL.

SPECIFICATION forming part of Letters Patent No. 341,818, dated May 11, 1886.

Application filed January 6, 1886. Serial No. 187,822. (No model.)

To all whom it may concern:

Be it known that we, JOHN H. RUSSELL and ASA W. PHELPS, of Springfield, in the county of Walworth and State of Wisconsin, have invented certain new and useful Improvements in Grinding-Mills, of which the following is a specification.

Our invention relates to that class of grinding-mills commonly known as "cylinder" and "concave," and has for its object the improvement of the mechanism by which the concave is supported and adjusted.

In the drawings, Figure 1 is a side elevation of our improved machine; Fig. 2, a top plan view; Fig. 3, a vertical central section at right angles to the axis of rotation; Fig. 4, a front end view; Fig. 5, a horizontal section of a portion of the grinding cylinder and concave, and Fig. 6 a detail view.

20 Our mill is designed to allow foreign matters—such as frequently find their way with the grain into the machine—to pass between the grinding-surfaces without injury to the latter; and to this end it consists in a novel 25 construction and arrangement of the spring-supporting devices for the concave, as herein-after described in detail, whereby the concave is permitted to yield both vertically and horizontally.

30 A indicates a substantial framing, consisting of uprights *a*, longitudinal timbers *b*, and cross-timbers *c*, the timbers *b* carrying boxes or bearings *d*, in which the axis or shaft *e* of roll or cylinder *B* rotates.

35 Mounted upon the shaft *e*, and secured thereto by the heads or disks *g*, is a metallic cylinder, *g'*, whose exterior is turned perfectly smooth, and upon said cylinder *g'* are secured, by means of screws *h*, the plates *f*, as shown 40 in Figs. 3 and 5. The interior cylinder, *g'*, forms a support for the grinding-plates *f* of the cylinder throughout their length. It will thus be seen that the plates of the cylinder can at any time be removed and new ones substituted, as in other machines of this class.

45 The cylinder *B* is provided with a band-wheel or pulley, *i*, by which motion is imparted to the cylinder from any convenient source.

50 C indicates the concave, composed of segmental plates *j*, corresponding to those of the cylinder, end plates, *k*, and tie-bolts *l*, as shown

in Figs. 1, 3, and 4, the concave being supported upon or by arms *D D*, pivoted at the rear of the machine in boxes *E E*. The boxes 55 *E E*, as shown in Figs. 1 and 3, slide upon the timbers *b*, and are guided and held in place by metal straps or guards *m*, secured to the timbers *a* and *b*. The boxes *E E* are also grooved on their under faces to receive webs or flanges 60 *p*, in order to prevent lateral displacement. A spring, *F*, bears at each end against the rear sides of the boxes *E*, and its tension is regulated and controlled by means of a setscrew, *n*, as shown in Figs. 1, 2, and 3. The 65 ends of the arms *D D* are bent laterally, as shown in Fig. 2, to form pintles or journals *o*, upon and from which, as a center, the arms *D* and concave *C*, carried thereby, rock. A screw, *G*, passes through each strap *m*, and 70 bears against the forward side of box *E* when the latter is in its normal position, and thereby regulates the distance between the cylinder and the concave in a horizontal line. A bar, *H*, connects the front ends of the arms *D D*, 75 as shown in Figs. 2, 3, and 4, said bar *H* being provided on its under side with a flat spring, *I*, having its ends slotted, as shown in Fig. 6, and guided by screws. The bar *H* is provided on its upper face with two screws, *J*, which, 80 when the mill is normally adjusted, are in contact with the under side of the cross-timber *c*, or a bracket, *q*, secured thereto.

K indicates a screw stem or rod passing freely through the bracket *q* and bar *H*, and headed 85 or enlarged at the under side of spring *I*, as shown in Figs. 3 and 4. The rod *K* is provided with a hand-wheel, *L*, having a threaded hub to screw on the rod *K*, and resting upon the upper side of the bracket *q*, so that as said 90 wheel is turned it raises or lowers the rod and varies the compression of the spring *I*.

A semicircular casing, *M*, corresponding in form to the concave *C*, is provided to cover the upper surface of the cylinder *B*, as shown 95 in Figs. 1, 3, and 4, the sheathing of the casing being turned upward at its upper rear edge to form one wall, *r*, of a hopper, *N*. The other end of the sheathing is extended laterally and downward, so as to form a guard, *s*, 100 and prevent the ground material from being thrown out too far. The sheathing on the front side of the concave is provided or formed with an upward extension, *t*, which, with the

wall *r* of the sheathing of the cylinder-casing, forms the hopper *N*, as shown in Figs. 1, 2, and 3.

O indicates the main hopper, supported on the frame *A* and delivering the material into the secondary hopper *N*. It will be seen that the upper casing, *M*, may at any time be removed, in order to have access to the cylinder and concave. Should any foreign matters be fed into the hopper *N* and between the cylinder and concave, they would strike against the front side of the latter and tend to dislodge the grinding-surfaces or spread the cylinder and concave apart. This would rock the concave *C* on its pivots *o*, depress the forward ends of bars *D D*, and allow the concave to move far enough away from the cylinder vertically to permit the obstruction to pass the throat or opening. This movement of the arms *D D* compresses the spring *I*, which latter returns the arms *D D* and the concave *C* back to their former positions as soon as it is relieved from undue pressure. As the obstacle works its way backward toward the discharge-outlet, the concave *C*, with its arms *D D* and boxes *E E*, is moved longitudinally or horizontally against the pressure of spring *F* sufficiently to allow the obstacle to be discharged. As soon as this is accomplished, the spring *F* returns the concave to its normal position.

When the machine is running empty, the springs *F* and *I* tend to bring the cylinder *B* and concave *C* in contact, and to prevent this the screws *G* and *J* are provided to limit the movement of the boxes *E E* and bar *H*, respectively.

Having thus described our invention, what we claim is—

1. In a grinding-mill, the combination, with a frame, of a cylinder, *B*, a concave, *C*, sliding boxes *E E*, and arms *D D*, supporting said concave and pivoted at their rear ends in said sliding boxes *E E*.

2. In a grinding-mill, the combination, with a frame, of a cylinder, *B*, a concave, *C*, arms *D D*, supporting said concave, sliding boxes *E E*, in which the arms *D D* are pivoted, and a spring, *F*, bearing against said boxes, as and for the purpose set forth.

3. In a grinding-mill, the combination, with a frame, of a cylinder, *B*, a concave, *C*, arms *D D*, supporting said concave and adapted to move vertically and horizontally, springs *F I*, arranged, substantially as shown, to return said arms and concave to their normal positions, and set-screws *G J*, to limit the movements of the concave.

4. In a grinding-mill, the combination, with a frame, of a cylinder, *B*, concave *C*, arms *D D*, supporting said concave and pivoted at one end, a cross-bar, *H*, connecting said arms at their other ends, a stem or rod mounted upon the frame and supporting the concave, a spring between the cross-bar and stem or rod, and a set-screw on the cross-bar to limit the movement of the latter.

5. The herein-described grinding-mill, consisting of frame *A*, cylinder *B*, concave *C*, arms *D D*, supporting the concave and pivoted at their rear ends in sliding boxes *E E*, a spring, *F*, to urge said boxes forward, set-screws *G* and *n*, for limiting the movement of the boxes *E E* and compression of spring *F*, respectively, cross-bar *H*, connecting the forward ends of bars *D D*, set-screw *J*, for limiting the upward movement of said cross-bar, a spring, *I*, on the under side of bar *H*, a rod or stem, *K*, carried by the frame and passing loosely through the bar *H* and secured to the spring *I*, and a hand-wheel, *L*, applied to the rod *K* to raise and lower the same.

JOHN H. RUSSELL.
ASA W. PHELPS.
